UNITED STATES PATENT OFFICE.

FRED S. JEWETT, OF LACONIA, NEW HAMPSHIRE.

STRIP-FASTENER.

1,130,295.

Specification of Letters Patent. Patented Mar. 2, 1915.

Application filed September 19, 1914. Serial No. 362,429.

To all whom it may concern:

Be it known that I, FRED S. JEWETT, a citizen of the United States of America, residing at Laconia, in the county of Belknap and State of New Hampshire, have invented certain new and useful Improvements in Strip-Fasteners, of which the following is a specification, reference being had to the accompanying drawings.

This invention relates to improvements in strip fasteners and particularly to improvements in fasteners for locking in place in a window-frame the strip commonly known as the parting bead; and an object of this invention is to provide a fastener or locking device of the character hereinbefore referred to which will be simple in construction, comparatively cheap in manufacture and efficient, convenient and durable in operation and use.

In the drawings illustrating the principle of this invention and the best mode now known to me of applying that principle, Figure 1 is an elevation of so much of a window-frame as is necessary to illustrate my invention; Fig. 2 is an elevation of a frame-member taken looking in the direction of the arrow A. Fig. 1; Fig. 3 is a section on the line B—B of Fig. 2; Fig. 4 is a detail showing a part of the window-frame; Fig. 5 is a detail showing a portion of the parting bead or strip; Fig. 6 is an other view of the parting bead or strip, the view being taken looking in the direction of the arrow C, Fig. 5; and Fig. 7 is a detail showing the key.

The parting bead or strip *a* lies between the window-sashes (not shown) and fits in the groove *b* formed in the inner edge of the window-frame or window-casing *c*. In the strip *a* there is mounted a transverse shaft *d* formed on its exterior with ring-shaped teeth *e*, which are so inclined as to permit the ready insertion of the shaft *d* but which prevent its withdrawal, as will be readily seen from the drawing (Fig. 3). The window-frame *c* is cut-away at *f*; and the wall *f'* of this cut-away portion or recess is engaged by the ends of the head *d'* of the lock-shaft *d* in the locking position of the latter (Fig. 2). The opposite end of the lock-shaft *d* is formed with a pair of

recesses or notches *d''* in which may be engaged the lugs *g* projecting laterally from one end of the key *h*. By turning the lock-shaft *d* by means of the key *h*, the head *d'* may be turned out of locking engagement with the wall *f'*, as will be readily seen from the dotted-line position in the drawing (Fig. 2); and, when the parting bead *a* is thus released, it may be readily withdrawn from the groove *b* formed in the window-frame *c*.

In accordance with the provisions of the patent statutes I have described the principle of operation of my invention, together with the apparatus which I now consider to represent the best embodiment thereof; but I desire to have it understood that the apparatus shown is only representative and that the invention can be carried out by other means.

I claim:

1. The combination of a window-frame member formed with a groove; a parting bead mounted in said groove; and a rotary locking device for locking and unlocking said bead to and from said window-frame member, said locking device being formed with teeth inclined to the longitudinal axis thereof and arranged to prevent movement of said device in one direction along said axis, when said device is turned.

2. The combination of a window-frame member formed with a groove; a parting bead mounted in said groove and formed with an aperture; and a locking device for locking and unlocking said bead to and from said window-frame member, said locking device comprising a T-headed rotatable shaft driven into said aperture and formed with teeth inclined to the longitudinal axis of said shaft and arranged to prevent the lengthwise movement of said shaft in the direction of the head thereof, when the shaft is turned.

Signed at Laconia, in the county of Belknap and State of New Hampshire, this sixteenth day of September, A. D. 1914, in the presence of the two undersigned witnesses.

FRED S. JEWETT.

Witnesses:
